UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 14,472, dated December 11, 1883.

Application filed July 23, 1883. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view 10 of a carpet, showing my new design. 15 The ground *a* is broken up into a number of irregularly-shaped, right-lined panels, variously ornamented by small mural and other

ornamentations. On this ground, at considerable distances apart, are scattered various loose sprigs of flowers and leaves. *A* is a sprig 20 of star-shaped flowers and flag-like leaves. *B* is a scattered group of star-shaped flowers, blossoms, and short leaves. *C* is a sprig of open flowers and oval leaves. *D* is a sprig of smaller flowers and leaves. Other flower- 25 sprays complete the design.

I claim—

The design for a carpet, substantially as shown and described.

WINTHROP L. JACOBS.
